UNITED STATES PATENT OFFICE.

GEORGE HOWARD NEIDLINGER, OF EAST ORANGE, NEW JERSEY, ASSIGNOR TO PEER-LESS TUBE CO., OF NEW YORK, N. Y., A CORPORATION OF NEW YORK.

COLLAPSIBLE TUBE FOR PASTE.

1,227,297.

Specification of Letters Patent. Patented May 22, 1917.

Application filed September 16, 1915. Serial No. 50,979.

To all whom it may concern:

Be it known that I, GEORGE H. NEIDLINGER, a citizen of the United States, and a resident of East Orange, in the county of 5 Essex and State of New Jersey, have invented a new and Improved Collapsible Tube for Paste, of which the following is a full, clear, and exact description.

This invention relates to collapsible tubes 10 for holding paste material.

The invention has to deal more particularly with means whereby the external surface of the tube can be printed in a plurality of colors expeditiously, accurately and 15 economically.

Heretofore in printing collapsible tubes in several colors great care was necessary on the part of the operator to so place the tubes on the printing mandrel as to insure 20 proper registration of the successive impressions. Considerable time and skill is required to properly place a tube on a mandrel, so that the cost of printing has been unduly large because of the limited 25 number of tubes that can be printed in a given time according to the old method.

The object of the present invention is to insure a proper placing of a tube on the mandrel so that successive colors will absolutely 30 register, this registering-insuring means being so designed that the attendant does not have to be especially skilled or experienced, as the mere placing of the tube longitudinally on the mandrel and turning 35 the tube back or forth will interlock the mandrel and tube, the interlocking means being so designed that the tube can be locked to the mandrel in only one position, so that the successive impressions or colors must 40 register. By this means the output of the printing machine is many times increased over the old method of operation.

For a more complete understanding of the invention, reference is to be had to the 45 following description and claims taken in connection with the accompanying drawing, wherein similar characters of reference indicate corresponding parts in all the views, and in which—

50 Figure 1 is a side view of an empty collapsible tube with a portion broken away to show the lug on the internal surface of the

head that engages with the mandrel to cause proper positioning of the tube;

Fig. 2 is an enlarged transverse section on 55 the line 2—2, Fig. 1;

Fig. 3 is an enlarged sectional view of the tube mounted on the mandrel and receiving an impression from the printing element; 60 and

Fig. 4 is a fragmentary detail view of a modified form of the invention.

Referring to the drawing, A designates a collapsible tube for holding paste stock, the tube comprising a pliable body 1, which, 65 when empty, is open at the end 2 and has a comparatively stiff head 3 provided with a discharge nozzle 4. On the head 3 and disposed internally of the tube is a suitable means adapted to interlock with the mandrel 70 that supports the tube during the printing of matter on the circumferential external surface of the tube. This means is preferably a lug 5 which is so shaped as to enter a recess or socket 6 in the end of the mandrel B of the 75 printing machine. The tube A is interlocked with or keyed to the mandrel by slipping the tube longitudinally on the latter and turning the tube in one direction or the other while maintaining an inward pressure 80 on the tube so as to cause the lug 5 to enter the recess 6, and when this is effected, the tube will be in the proper position to receive an impression. This act is repeated 85 every time the tube is placed on the mandrel to receive another impression of color, and since the tube can have only one position on the mandrel it follows that all the impressions are positively registered. The lug 5 may be of any desired shape, and if desired 90 the lug may be placed on the mandrel, as indicated at 5', Fig. 4, and the depression or recess 6' may be arranged in the head of the tube.

In Fig. 3 the printing element C is shown 95 in the act of printing an impression on the tube, which is rotated with the mandrel.

From the foregoing description taken in connection with the accompanying drawing, the advantages of the construction and 100 method of operation will be readily understood by those skilled in the art to which the invention appertains, and while I have described the principle of operation, together

with the article which I now consider to be the best embodiment thereof, I desire to have it understood that the article shown is merely illustrative and that such changes may be made when desired as fall within the scope of the appended claims.

Having thus described my invention, I claim as new and desire to secure by Letters Patent:

- 10 1. A collapsible paste-holding tube having on the inner surface of its head means for interlocking with the mandrel of a printing machine to insure registering of successive impressions printed on the tube.
- 15 2. A collapsible tube for holding paste, comprising a body, a head on one end thereof, a discharge nozzle at the center of the head, and a lug on the internal surface of the head for engaging a mandrel of a print-

ing machine to insure registering of impressions successively applied to the external surface of the body.

3. A collapsible tube for holding paste or the like, comprising a tubular body of round cross-section, a head at one end of the body, a discharge opening at the center of the head, and integral means on the internal surface of the head for interlocking with a mandrel of a printing machine for insuring registering of successive impressions.

In testimony whereof I have signed my name to this specification in the presence of two subscribing witnesses,

GEORGE HOWARD NEIDLINGER.
